(57) **CLAIM**

We claim the ornamental design for a utensil bowl, as shown and described.

DESCRIPTION

FIG. 1 is a top perspective view of the utensil bowl showing our new design;

FIG. 2 is a top plan view thereof;

FIG. 3 is a right side elevation view thereof, the opposite side being a mirror image;

FIG. 4 is a bottom plan view thereof;

FIG. 5 is a front elevation view thereof;

FIG. 6 is a rear elevation view thereof;

FIG. 7 is a top perspective view of FIG. 1 shown in an alternate environment;

FIG. 8 is a right side elevation view of FIG. 7, the opposite side being a mirror image;

FIG. 9 is a front elevation view of FIG. 7; and,

FIG. 10 is a rear elevation view of FIG. 7.

The ornamental design which is claimed is shown in solid lines in the drawings. The broken lines in the drawings are for illustrative purposes only and form no part of the claimed design.
